UNITED STATES PATENT OFFICE.

EUGENE A. WALTERS AND HENRY L. AYRES, OF WALWORTH, WISCONSIN.

CLEVIS.

SPECIFICATION forming part of Letters Patent No. 340,838, dated April 27, 1886.

Application filed March 4, 1884. Serial No. 122,944. (No model.)

To all whom it may concern:

Be it known that we, EUGENE A. WALTERS and HENRY L. AYRES, citizens of the United States, residing at Walworth, in the county of Walworth and State of Wisconsin, have invented certain new and useful Improvements in Clevises; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to clevises; and it consists in the novel construction, combination, and arrangement of parts, as will be herein-after fully described and claimed.

In the drawings, Figure 1 is a side view; 20 Fig. 2, a plan view; Fig. 3, a detached sectional view showing the joint between the latch and hook, all of which will be described.

The clevis proper, A, has its arms A' connected at their ends by the transverse bolt B, 25 which is removable therefrom to enable the detachment of the device from one implement when it is desired to use it on another. In the crown A² of the clevis proper we form an opening, through which is inserted the 30 rear end, C', of the latch C, which extends within the clevis A, and is held by a transverse pin C². A shoulder, C⁴, is formed on the latch above the clevis A, and the latch between said shoulder C⁴ and pin C² journals 35 in the head of the clevis, so it may freely turn, as will be understood from the drawings. The latch in advance of the shoulder C⁴ is flattened and has its outer or forward end bent upward, forming a tongue, C³, the extremity 40 of which is beveled or cut off in a line approximately parallel with that of the length of the latch, as shown in Figs. 1 and 3. The object of thus forming the extremity of the tongue is to furnish a broad bearing for the 45 point of the hook, as will be seen.

The hook D has its rear end bifurcated or slotted at D', so as to fit over the latch, and is pivoted thereto at about the point of bending the tongue therefrom, as shown in Figs. 1 and 50 3. The base-wall D² of the slot D' is formed

and adapted to engage the inner edge of the tongue C³, when the hook is opened or carried forward into the position indicated in dotted lines, Fig. 2.

It will be noticed that the wall D² is inclined, 55 so as to coincide and rest flat against the tongue when in the dotted position, Fig. 1. This angle of the wall D² has another object. It will be noticed that in use the hook is ordinarily as seen in the position shown in Fig. 2, 60 the back of the hook being toward the ground and the point of same projecting up; but frequently in use the hook will be dropped to the ground. If in such case dirt should get in between the hook and latch, the desired movements thereof may be clogged and prevented. 65

It will be noticed that by inclining the wall as shown we are able to fit the lower edge, d, 70 of the slot close against the under edge of the latch, thus excluding all dirt from the joint, as will be understood from the drawings.

The joint of the hook is curved over and bears, in the position shown in Fig. 1, on the end or extremity of the tongue, said bearing serving as a stop in the backward movement 75 of the hook, and the inclined shoulder D² as a bearing in the forward movement of same, as indicated in Fig. 1. By lapping the jaws D³ on opposite sides of the latch we remove from the pivot-pin all lateral strain—such as is 80 caused in turning the plow and bringing such strain onto the jaws—as will be understood, thus obviating the breakage of the pin in the operation of turning or otherwise when under lateral strain. By this removable cross-bar the 85 clevis may be readily detached from one plow or harrow or other implement and attached to another one, as may be desired.

We are aware that a patent has been granted one Bednar, No. 217,194, for a clevis formed of 90 a latch-bar, and a hook pivoted to one side thereof, and having its point arranged to coincide with the point or outer end of the latch when its edge shoulders engage stops formed by a lateral rib on the shank. This we do not 95 claim, but seek to protect ourselves in the formation of the joint between the latch and hook by bifurcating or slotting the hook, as shown. By this we take the lateral strain on the hook, which may occur in turning and 100

otherwise, off the pivot-pin and place same on the stronger parts, as clearly shown; also, the base of the slot in the hook forms a stop which cannot fail to serve its purpose, no matter what lateral bending may be given the hook. This wall in our device is sloped or inclined for the purpose of providing a broad bearing flat against the inner edge of the tongue, and also to exclude dirt, as before described, and the point of the hook being bent back to engage the top of the tongue or latch, the flange-rib and stop-shoulders of the above device are dispensed with. We are also aware that heretofore hooks have been journaled in one end of a continuous link, and that such a construction is shown in the book of farm implements published by Henry Stephens in 1858. Our invention differs from the said device in that the clevis has a detachable bar, whereby the improvement may be interchangeably used on different implements. It also differs from the said device in the journaling, not of the hook, but the latch in the clevis, and in the peculiar form of joint between the tongue and hook, as hereinbefore described. It will be seen that the clevis-loop A is pivoted at one end, and its other end may swing freely on such pivot. In the swinging end of this clevis is journaled the stem c, so that it can rotate freely. We thus get two motions—one of the clevis on its pivot and the other of the stem in the swinging end of the clevis. To the rotating stem we pivot one end of the hook D, so that the said hook may turn on its connection with the stem. Thus we get a third movement. By these three movements the hitching attachment will give or adjust into any line of draft that may be exerted on it, and this can only be secured by the three pivots before described. In operation, if the parts are in the position shown in Fig. 1 and draft be exerted on the hook D at right angles to the plane of such hook, the said hook will rotate until it rests in the plane of such draft,

when its hook will readily adjust itself to the lines thereof. Again, any torsional strain on the hook, incident to the twisting of the draft chain or hook, is overcome by the rotation of the stem. This free movement of the parts enables a ready adaptation to any line of strain or draft, and prevents any fracture or damage to the parts, resulting from a sudden strain in any direction when the connections are rigid. We are aware that it is not new to journal a snap-hook in the swinging end of a clevis; but in this case the hook is journaled in the clevis and has no movement except a rotation in its bearing. Heretofore, also, hooks have been pivoted to stems or shanks; but in such instances the stem is not journaled in a clevis, link, or bearing. We are not aware, however, that hitching attachments have ever been formed of a clevis pivoted at one end, a stem journaled in the swinging end of such clevis, and a hook pivoted at one end to such stem, whereby to secure the universal adaptation to the various lines of draft, as before fully described. We therefore do not broadly claim any of the construction shown in the patent to Bednar, or in the farm-implement book above adverted to; but,

Having described our improvement, what we claim, and desire to secure by Letters Patent, is—

A clevis consisting of the following elements in combination: a link, a draft-latch swiveled therein, and a hook pivoted to the draft-latch and limited in its forward and backward movement thereby, the parts being arranged and operating substantially as and for the purposes specified.

In testimony whereof we affix our signatures in presence of two witnesses.

EUGENE A. WALTERS.
HENRY L. AYRES.
